UNITED STATES PATENT OFFICE.

SAMUEL I. VAN DERSAL, OF ST. PAUL, MINNESOTA, ASSIGNOR OF ONE-HALF TO C. H. GOUGH, OF KANSAS CITY, MISSOURI.

DESIGN FOR A CAMPAIGN-BADGE.

SPECIFICATION forming part of Design No. 37,126, dated September 13, 1904.

Application filed June 13, 1904. Serial No. 212,435. Term of patent 3½ years.

To all whom it may concern:

Be it known that I, SAMUEL I. VAN DERSAL, a citizen of the United States, residing at St. Paul, in the county of Ramsey and State of Minnesota, have invented a certain new, original, and ornamental Design for Campaign-Badges, as illustrated by the accompanying drawing, which represents a face view of the same.

What I claim as new, and desire to secure to by Letters Patent, is—

The ornamental design for a campaign-badge, substantially as shown.

SAMUEL I. VAN DERSAL.
